SHOE

Herbert Rosenbaum, Chestnut Hill, Mass., assignor to Andrea Shoe Corp., Villalba, Puerto Rico, a corporation of Puerto Rico

Filed Aug. 16, 1965, Ser. No. 86,581

Term of patent 14 years

(Cl. D7—5)

FIG. 1 is a bottom plan view of a shoe showing my new design;

FIG. 2 is a side elevational view thereof, the side opposite being substantially similar thereto;

FIG. 3 is a cross sectional view taken on line 3—3 of FIG. 2; and

FIG. 4 is a cross sectional view taken on line 4—4 of FIG. 2.

The dominant features of my new design reside in the full line disclosure on the drawing.

I claim:

The ornamental design for a shoe, as shown and described.
